US00D527161S

(12) **United States Design Patent** (10) **Patent No.:** **US D527,161 S**
(45) **Date of Patent:** **** Aug. 29, 2006**

(54) **EXTRUDED CONFECTION**

(75) Inventors: **Charles Lucas**, Chicago, IL (US);
Michael J. Feilen, Wheaton, IL (US)

(73) Assignee: **QA Products, Inc.**, Elk Grove Village,
IL (US)

(**) Term: **14 Years**

(21) Appl. No.: **29/232,588**

(22) Filed: **Jun. 21, 2005**

(51) **LOC (8) CL.** **01-01**

(52) **U.S. CL.** **D1/108; D1/120; D1/127**

(58) **Field of Classification Search** D1/106,
D1/108, 120, 126-129; D11/49, 57, 82; 426/96,
426/104, 143, 440, 445, 449-50, 514-5,
426/621, 625, 658, 660

(57) **CLAIM**

We claim the ornamental design for an extruded confection,
as shown and described.

DESCRIPTION

FIG. 1 is a perspective view of an extruded confection of the
present invention;

FIG. 2 is a front view thereof;

FIG. 3 is a back view thereof;

FIG. 4 is a top view thereof;

FIG. 5 is a right side view thereof;

FIG. 6 is a left side view thereof; and,

FIG. 7 is a bottom view thereof.
